UNITED STATES PATENT OFFICE.

GEORGE ERTEL, OF QUINCY, ILLINOIS.

BALING-PRESS.

SPECIFICATION forming part of Letters Patent No. 336,305, dated February 16, 1886.

Application filed December 15, 1885. Serial No. 185,724. (No model.)

To all whom it may concern:

Be it known that I, GEORGE ERTEL, of Quincy, in the county of Adams and State of Illinois, have invented a new and useful Improvement 5 in Baling-Presses, of which the following is a full, clear, and exact description.

My invention relates to presses for baling hay, straw, or other material, and has for its object to provide a simple, inexpensive, and 10 effective arrangement of devices by which the power applied at the sweep is made to operate the plunger in the press-box.

The invention consists in certain novel features of construction and combinations of parts 15 of the power-connections between the sweep and the plunger, all as hereinafter fully set forth.

Reference is to be had to the accompanying drawings, forming a part of this specification, 20 in which similar letters of reference indicate corresponding parts in both the figures.

Figure 1 is a vertical sectional elevation of 25 a portion of a baling-press embodying my improvement, and Fig. 2 is a plan view of the improvement, and shows the press-box in horizontal section.

The metal head A, to which the sweep B is connected by the pivot pin or bar C, has elongated bosses or hubs *a a* at each side, which 30 extend to the upper and lower metal plates D D', which are secured to the top and bottom frames E E' of the press, and through the press-frame and the hubs *a a* and main body of the head A is passed a heavy spindle or bolt, F, by which the head and its sweep B are pivoted 35 to the press-frame, so as to be swung in horizontal plane. A brace, G, hung on the pivot-bolt F, and held by a suitable bracket or catch, g, to the sweep, holds the latter up at the outer 40 end in proper operative position.

At the center of the rounded part A' of the head A is fastened by a pin or bolt, h, one end 45 of a chain, H, and the other end of the chain is connected by a pin or bolt, h', to the back end of the pitman I, by which the follower J is forced forward in the press-box K to form the bale, as presently explained. The chain H enters a groove, *a*, in the edge of the head A as the sweep is turned to either side of the 50 press-frame. The sweep-head A has a semi-annular vertically-ranging opening, *a*', within which turns freely the hub or sleeve portion *l*

of the metal yoke L, which is pivoted to the top and bottom parts of the press-frame by a heavy pin or bolt, M, which passes through its 55 hub *l*. The upper and lower arms *l'* and *l''* of the yoke L extend, respectively, above and below the pitman I, to which they are pivoted by a pin or bolt N at a point a little forward 60 of the end of the pitman to which the chain H is attached. Thus arranged, the sweep-head A and yoke L have free independent movement on their respective pivots F M.

In operating the press, as the sweep B is moved in the direction of the arrow *x* in Fig. 65 2 from a position at a right angle to the press frame or case to a position in line therewith, and indicated in Fig. 1, the follower J will be forced forward to press the material in the box K, and as the motion of the sweep carries the 70 pitman I past the longitudinal center of the press just after the follower receives its extreme forward movement the expansion of the 75 pressed material in the box K against the follower will carry it back, and the pitman I and chain H will be thrown to the position indicated by dotted lines in Fig. 2, ready for the return-stroke of the sweep, which movement will again 80 force the follower forward, as will readily be understood. Passing the hub or sleeve *l* of 85 yoke L through the opening *a*' of the sweep-head A not only allows the head and yoke to have free independent movement on their respective pivots, but this arrangement of parts provides for a greater length of stroke of the 90 pitman and follower for a given radius of the sweep than can be secured by other constructions. Furthermore, the passage of the yoke-hub through the sweep-head allows the hub to be extended to fit between the upper and lower 95 parts of the press-frame, whereby the yoke has a very substantial and steady support in the press-frame, and whereby also the yoke-pivot M will not be cut by the swinging of the yoke on it, and by making the sweep-head A with 100 the bosses *a a* fitting between the top and bottom parts of the frame the sweep-pivot F will not be cut by the turning of the sweep on it, and the head and sweep will have substantial support in operative positions.

Having thus fully described my invention, I claim as new and desire to secure by Letters Patent—

1. The combination, in a baling-press and

- with the sweep-head A, pivoted at F to the press-frame and provided with the semi-annular opening a^2 , the pitman I, and the chain H, connected to the sweep-head at h and to the beam at h' , substantially as specified, of the yoke L, pivoted on a pin, M, passing through the opening a^2 of the sweep-head and pivoted at N to the pitman, substantially as and for the purposes set forth.
- 5 2. In a baling-press, the pivoted sweep-head A, provided with an opening, a^2 , in combination with the yoke L, formed in one piece with a hub, l, pivoted on a bolt, M, passing through the head-opening a^2 , and with arms $l' l''$ and connections, substantially as specified, between the sweep-head, pitman, and yoke, as and for the purposes herein set forth.
- 10 3. In a baling-press, the combination, with the sweep-head A, pivoted to the press-frame and provided with an opening, a^2 , of the yoke L, pivoted by its hub l on a pin, M, passing through the sweep-head opening a^2 , and said hub l fitting between the top and bottom parts
- 15 of the press-frame, and connections, substantially as specified, between the sweep-head, 25 pitman, and yoke, as and for the purposes set forth.
4. In a baling-press, the combination of the sweep-head A, formed in one piece and pivoted on a pin, F, to the press-frame, and made with 30 bosses a a fitting between the top and bottom parts of the press-frame, and provided with an opening, a^2 , the yoke L, formed in one piece with a hub, l, fitting between the top and bottom parts of the press-frame, and pivoted on 35 a pin, M, passing through the head-opening a^2 , and having arms $l' l''$, the pitman I, a pin, N, pivoting the yoke to the beam, and a chain, H, connected at h to the sweep-head and at h' to the pitman, substantially as and for the 40 purposes herein set forth.

GEORGE ERTEL.
